Primary Examiner — Robert M Spear*Assistant Examiner* — Ryan Harvey(74) *Attorney, Agent, or Firm* — Wessels & Arsenault, L.L.C.; John A. Arsenault; Daniel Dubuisson(57) **CLAIM**

The ornamental design for an exercise platform, as shown and described.

DESCRIPTION

FIG. 1 is a top perspective view of an exercise platform showing my new design;

FIG. 2 is a front elevational view thereof;

FIG. 3 is a top plan view thereof;

FIG. 4 is a bottom plan view thereof; and,

(Continued)

FIG. 5 is a right side elevational view thereof.
The broken lines shown in the drawings represent portions
of the exercise platform that form no part of the claimed
design.
